ROLLER SKATE

Raymond W. Berg, 854 Figueroa Terrace,
Los Angeles, Calif. 90012

Filed July 11, 1974, Ser. No. 487,579

Term of patent 14 years

Int. Cl. D21—02

U.S. Cl. D34—14 C

FIG. 1.

FIG. 2.

FIG. 3.

FIG. 4.

FIG. 1 is a side elevational view of a roller skate embodying my new design;

FIG. 2 is a top plan view thereof;

FIG. 3 is a front elevational view thereof;

FIG. 4 is a rear elevational view thereof.

The bottom of the skate is unornamented.

I claim:

The ornamental design for a roller skate, substantially as shown and described.
